UNITED STATES PATENT OFFICE.

FREMONT CHESTER, OF ROCHESTER, NEW YORK.

DESIGN FOR A SIGN.

Application filed November 28, 1927. Serial No. 24,317. Term of patent 7 years.

To all whom it may concern:

Be it known that I, FREMONT CHESTER, a citizen of the United States, residing at Rochester, in the county of Monroe and State of New York, have invented a new, original, and ornamental Design for Sign, of which the following is a specification, reference being had to the accompanying drawing, forming part thereof.

Fig. 2 is a side view of the same.

I claim:

The ornamental design for a sign, as shown.

In testimony whereof I affix my signature.

FREMONT CHESTER.
